β -HALOETHYLAMINES

James F. Kerwin and Glenn E. Ulliyot, Philadelphia, Pa., assignors to Smith, Kline & French Laboratories, Philadelphia, Pa., a corporation of Pennsylvania

No Drawing. Application December 15, 1948,
Serial No. 65,508

6 Claims. (Cl. 260—570.7)

1

This invention relates to new compositions of matter having desirable physiological properties, more particularly adrenolytic or sympatholytic properties.

The new compounds according to this invention are β -haloethylamines with the nitrogen linked to the 7-position of the acenaphthene ring system and have the general formula:

in which Z is a member of the group consisting of lower alkyl groups, lower alkenyl groups, phenylalkyl groups, the alkyl portion of which does not exceed 4 carbon atoms, and methoxy-substituted phenyl alkyl groups, the alkyl portion of which does not exceed four carbon atoms.

R₁ and R₂ are members of the group consisting of hydrogen and methyl groups.

X is a member of the group consisting of chlorine and bromine.

This invention also contemplates the organic and inorganic salts of the compounds having the general formula above such as will be readily formed with, for example, organic and inorganic acids such as hydrochloric, sulfuric, sulfamic, tartaric, hydrobromic, glycolic, phosphoric, succinic, maleic, acetic, and the like.

More specifically within the general formula above, this invention contemplates compounds having the following more specific formula:

in which Z is a member of the group consisting of:

1. Alkyl groups having not in excess of 8 carbon atoms, i. e., methyl, ethyl, propyl, butyl, amyl, hexyl, heptyl and octyl groups.

2. Alkenyl groups having not in excess of 8 carbon atoms, i. e., propenyl, butenyl, pentenyl, hexenyl, heptenyl and octenyl groups.

3. Aralkyl groups the alkyl portion of which comprises methylene, ethylene, propylene and butylene radicals, i. e., the alkyl portion does not exceed 4 carbon atoms.

4. Substituted aralkyl groups the alkyl portion of which comprises methylene, ethylene,

propylene and butylene radicals, i. e., the alkyl portion does not exceed 4 carbon atoms, and the substitution is of a member of the group consisting of:

5. (a) OH.
- (b) Ethyl, methyl, propyl and butyl.
- (c) Alkoxy groups, the alkyl portion of which comprises ethyl, methyl, propyl and butyl, i. e., does not exceed 4 carbon atoms.
- 10 (d) Fluorine.
- (e) Bromine.
- (f) Chlorine.
- (g) Amino groups.
- (h) Acylamino groups, the acyl group of which comprises formyl, acetyl, propionyl, butyryl, valeryl, caproyl, heptyl and capryl, i. e., does not exceed 8 carbon atoms.
- 15 (i) Alkylamino groups, the alkyl portion of which comprises ethyl, methyl, propyl and butyl, i. e., does not exceed 4 carbon atoms.
- 20 (j) Alkoxyethyl groups, the alkoxy portion of which comprises methoxy, ethoxy, propoxy, butoxy, amyoxy, hexyloxy, heptyloxy, and octyloxy groups; i. e., does not exceed 8 carbon atoms.
- 25 (k) Aryloxyalkyl groups, the alkyl portion of which comprises ethylene, propylene, butylene radicals, i. e., does not exceed 4 carbon atoms.
- 30 (l) Substituted aryloxyalkyl groups, the alkyl portion of which comprises ethylene, propylene, butylene radicals, i. e., does not exceed 4 carbon atoms and in which the substitution is a member of the group consisting of:
  - (a) OH.
  - (b) Ethyl, methyl, propyl and butyl.
  - (c) Alkoxy groups, the alkyl portion of which comprises ethyl, methyl, propyl and butyl, i. e., does not exceed 4 carbon atoms.
  - (d) Fluorine.
  - (e) Bromine.
  - (f) Chlorine.
  - (g) Amino groups.
  - (h) Acylamino groups, the acyl group of which comprises formyl, acetyl, propionyl, butyryl, valeryl, caproyl, heptyl, capryl, i. e., does not exceed 8 carbon atoms.
  - (i) Alkylamino groups, the alkyl portion of which comprises ethyl, methyl, propyl and butyl, i. e., does not exceed 4 carbon atoms.
  - (j) Cyclopentyl and cyclohexyl groups.
  - (k) Cyclopentylalkyl and cyclohexylalkyl groups, the alkyl portion of which comprises methylene, ethylene, propylene, butylene, amylene, hexylene.
  - (l) A phenyl group.
  - (m) A substituted phenyl group, in which the

substitution is a member of the group consisting of:

- (a) OH.
- (b) Ethyl, methyl, propyl and butyl.
- (c) Alkoxy groups, the alkyl portion of which comprises ethyl, methyl, propyl and butyl, i. e., does not exceed 4 carbon atoms.
- (d) Fluorine.
- (e) Bromine.
- (f) Chlorine.
- (g) Amino groups.
- (h) Acylamino groups, the acyl group of which comprises formyl, acetyl, propionyl, butyryl, valeryl, caproyl, heptyl and capryl, i. e., does not exceed 8 carbon atoms.

(i) Alkylamino groups, the alkyl portion of which comprises ethyl, methyl, propyl and butyl, i. e., does not exceed 4 carbon atoms.

R, R₁ and R₂ are members of the group consisting of hydrogen and alkyl groups consisting of methyl, ethyl, propyl, butyl, amyl and hexyl, the substituents for R, R₁, and R₂ being selected so that the sum of the carbon atoms thereof does not exceed six carbon atoms.

X is a member of the group consisting of chlorine and bromine.

The inorganic and organic salts such as will be readily formed with, for example, inorganic and organic acids, such as hydrochloric, sulfuric, sulfamic, tartaric, glycolic, phosphoric, succinic, maleic, hydrobromic, acetic, and the like, are contemplated as included within this invention.

The compounds contemplated by this invention may be prepared by various procedure. However, as generally illustrative of procedure for the preparation of the several compounds and as exemplifying preferred procedure for their preparation, they will variously be prepared by a two step process which will be made apparent by the following scheme:

It will be appreciated that in the above scheme illustrative of the process for preparing compounds in accordance with this invention X, Z, R₁ and R₂ represent the atoms in groups as designated with reference to the above general formula for the compounds contemplated by this invention.

In proceeding for the preparation of compounds according to this invention, the starting material 7-chloroacenaphthene or 7-bromoacenaphthene may be readily prepared by reacting 7-acenaphthol and thionyl chloride or thionyl bromide in the presence of pyridine. By way of

example 7-chloroacenaphthene will melt at 38°-39° C.

The reaction between 7-chloroacenaphthene or 7-bromoacenaphthene and the amino alcohol, i. e., the first step in the process exemplified above, will be carried out conveniently in an inert solvent, such, for example, as benzene, toluene, xylene, or the like. An excess of the amino alcohol may be used to remove the hydrogen halide formed in the reaction or, as will be obvious to those skilled in the art, another acid binding agent may be employed. The amino alcohol product of the first step may be isolated as free base by distilling off the solvent or may be converted into a hydrohalide salt by obvious procedure and purified by recrystallization.

To obtain the end product, the intermediate amino alcohol, product of the first step of the process as illustrated, either as the free base or as a hydrohalide salt, is heated with any one of the commonly used agents for replacing a hydroxyl group by a halogen such, for example, as thionyl chloride, thionyl bromide, concentrated hydrobromic acid, concentrated hydrochloric acid, or the like, it being, we believe, apparent that the end product is obtained from the intermediate amino alcohol by replacing the reactive hydroxyl group with chlorine or bromine.

The β -chlorethylamine or β -bromethylamine end product is obtained as a hydrohalide salt. The salt may be readily converted to the free base by interaction with one equivalent of a strong base, as, for example, sodium hydroxide, in usual and well known manner, for example, by the addition of the strong base to a cold aqueous solution of the salt. The free base may be isolated by rapid extraction into an organic solvent such as ether or benzene.

For the preparation of any desired inorganic or organic salt, the free base will be reacted in usual well known manner with the appropriate inorganic or organic acid.

As more specifically illustrative of compounds in accordance with this invention and of specific procedure for the preparation thereof, the following examples will exemplify compounds of the several types contemplated and procedure for the preparation thereof and will, in connection with the foregoing general definition of the compounds contemplated and their preparation, make apparent to those skilled in the art the structure of all the several compounds contemplated by this invention and procedure for their preparation:

EXAMPLE 1
N-(7-acenaphthyl)-N-ethyl- β -chlorethylamine hydrochloride

A solution of 20.5 g. of 7-chloroacenaphthene, 19 g. of ethylamino-ethanol in toluene is heated for three hours between 85-100° C. Ether is added to the cooled reaction mixture and the precipitated ethylaminoethanol hydrochloride removed by filtration. The filtrate is washed with water, dried over anhydrous potassium carbonate and acidified with anhydrous hydrogen chloride. Recrystallization of the hydrochloride from alcohol and ether containing a small amount of dry hydrogen chloride gives a colorless solid which melts at 150.5°-152.5° C.

5

Seventeen grams of *N*-(7-acenaphthyl)-*N*-ethylaminoethanol hydrochloride is suspended in dry chloroform and a solution of 8.8 g. of thionyl chloride in 20 ml. of chloroform is added with cooling. The reaction mixture is then heated at 35° C. for one-half hour and finally heated to reflux for one and one-half hours. The solvent is removed under reduced pressure and the product *N*-(7-acenaphthyl)-*N*-ethyl- β -chlorethylamine hydrochloride is recrystallized from alcohol and ether. It melts at 197.5-198° C.

The product obtained in the form of its hydrochloride will be readily converted to the free base by treatment thereof in cold aqueous solution with one equivalent of sodium hydroxide in well known manner. The free base may be isolated from the mixture by quickly extracting it with an organic solvent such as ether or benzene.

Organic and inorganic salts will be prepared by adding the desired organic or inorganic acid to a solution of the free base in, for example, ether, in the usual and well known manner.

EXAMPLE 2

N-(7-acenaphthyl)-*N*-benzyl- β -chlorethylamine hydrochloride

Seventy-two grams of 7-chloroacenaphthene, 116 g. of benzylaminoethanol and 140 ml. of benzene are stirred at 75° C. for fourteen hours. Ether is added to the cooled reaction mixture and the benzylaminoethanol hydrochloride is removed by filtration. Addition of dry hydrogen chloride to the filtrate forms *N*-(7-acenaphthyl)-*N*-benzylaminoethanol hydrochloride which, after recrystallization from alcohol, melts at 228-230° C.

A mixture of 34 grams of *N*-(7-acenaphthyl)-*N*-benzylaminoethanol hydrochloride, 14.3 g. of thionyl chloride and 250 ml. of chloroform is refluxed for two hours. The solvent is removed by distillation under reduced pressure and the residue is recrystallized from n-amyl alcohol. *N*-(7-acenaphthyl)-*N*-benzyl- β -chlorethylamine hydrochloride melts at 196-197.5° C.

The free base and inorganic and organic salts thereof will be obtained as heretofore made perfectly apparent.

EXAMPLE 3

N-(7-acenaphthyl)-*N*-methyl- β -chlorethylamine hydrochloride

This compound will be prepared by the procedure of Example 1 using an equivalent amount of methylaminoethanol instead of ethylaminoethanol.

The free base and inorganic and organic salts thereof will be obtained as heretofore made perfectly apparent.

6

EXAMPLE 4

N-(7-acenaphthyl)-*N*-(iso-isoamyl)- β -chlorethylamine hydrochloride

The procedure of Example 1 will be used with the ethylaminoethanol replaced by an equimolar amount of isoamylaminoethanol.

15 The free base and inorganic and organic salts thereof will be obtained as heretofore made perfectly apparent.

EXAMPLE 5

N-(7-acenaphthyl)-*N*-allyl- β -chloroethylamine hydrochloride

30 This compound will be formed by reaction of 7-chloroacenaphthene with allylaminoethanol and further reaction of the product with thionyl chloride by the method described under Example 1.

35 The free base and inorganic and organic salts thereof will be obtained as heretofore made perfectly apparent.

EXAMPLE 6

N-(7-acenaphthyl)-*N*-ethyl-1-amino-2-chloropropane hydrochloride

50 This compound will be made in the same manner as Example 1 except that 1-ethylamino-2-propanol will replace ethylaminoethanol in the first step of the synthesis.

55 The free base and inorganic and organic salts thereof will be obtained as heretofore made perfectly apparent.

EXAMPLE 7

N-(7-acenaphthyl)-*N*-ethyl-2-amino-1-chloropropane hydrochloride

70 The procedure of Example 1 will be followed with 2-ethylamino-1-propanol used in place of ethylaminoethanol.

75 The free base and inorganic and organic salts thereof will be obtained as heretofore made perfectly apparent.

EXAMPLE 8

N - (7 - acenaphthyl) - N - (p - methoxy - phenylisopropyl) - β - chlorethylamine hydro - chloride

This compound will be prepared as described under Example 2 except that p-methoxyphenylisopropylaminoethanol will be used instead of benzylaminoethanol.

The free base and inorganic and organic salts thereof will be obtained as heretofore made perfectly apparent.

From the above general and specific disclosure all of the several compounds and inorganic and organic salts thereof contemplated by this invention are made perfectly apparent to those skilled in the art, it being only necessary for the chemist to substitute the atoms and groups, all of which are common and well known to the chemist, corresponding to any particular compound or salt thereof in the general formulae given.

From the foregoing general and specific disclosure of procedure for the preparation of the compounds and salts thereof contemplated by this invention, it is apparent to those skilled in the art that all the compounds and salts will be prepared by the procedure described and exemplified by the mere use in step 1 of the reagents corresponding to any particular compound desired, the reagents for any particular compound being either well known or prepared by the procedure indicated and affording no problem to the chemist.

As has been indicated, while in the foregoing examples the products in accordance with this invention are exemplified by their hydrochloride salts, the several examples will serve as specific examples of free bases by the mere elimination from the several formulae given of the radical HCl. As has been indicated, the free bases will be obtained from the hydrohalide salts by usual and well known procedure comprising treatment with an inorganic base such as sodium carbonate, sodium hydroxide, or the like. The above general formula will serve as specifically exemplifying all the several compounds embraced thereby by a mere substitution in the formula for Z, R₁, R₂ and X of the substituents given therefor in connection with the formula.

What we claim and desire to protect by Letters Patent is:

1. β -Haloethylamines having the structurein which Z is a member of the group consisting of lower alkyl groups, lower alkenyl groups, phenylalkyl groups, the alkyl portion of which does not exceed 4 carbon atoms, methoxy-substituted phenylalkyl groups, the alkyl portion of which does not exceed 4 carbon atoms; R₁ and R₂ are members of the group consisting of hydrogen and methyl; and X is a member of the group consisting of chlorine and bromine; and acid addition salts of said compounds.

2. A compound having the formula:

3. A compound having the formula:

4. A compound having the formula:

5. A compound having the formula:

6. A compound having the formula:
